UNITED STATES PATENT OFFICE.

JAMES D. WALSH, OF ST. LOUIS, MISSOURI.

FEED MECHANISM FOR POLISHING-MACHINES.

No. 821,143.

Specification of Letters Patent.

Patented May 22, 1906.

Application filed July 24, 1905. Serial No. 271,027.

To all whom it may concern:

Be it known that I, JAMES D. WALSH, a subject of the King of Great Britain, residing at St. Louis, State of Missouri, have invented 5 certain new and useful Improvements in Feed Mechanism for Polishing-Machines, of which the following is a full, clear, and exact description, reference being had to the accompanying drawings, forming a part hereof.

10 My invention has relation to improvements in feed mechanism for pipe-polishing and similar machines; and it consists in the novel construction and arrangement of parts more fully set forth in the specification and 15 pointed out in the claims.

In the drawings, Figure 1 is a general side elevation of a polishing-machine, showing 20 my invention applied thereto. Fig. 2 is a vertical transverse section on the line 2 2 of Fig. 1. Fig. 3 is a section on the vertical line 25 3 3 of Fig. 1. Fig. 4 is a section on the vertical line 4 4 of Fig. 1. Fig. 5 is an enlarged elevational detail of the link traveling over the smooth or unthreaded portion of the screw-shaft and of the belt-collar coupled thereto. Fig. 6 is an enlarged horizontal sectional detail of the traveling nut of the link passing over the threaded portion of the screw-shaft. Fig. 7 is a sectional and elevational detail of the adjustable or tail chuck for the pipe. Fig. 8 is an elevational detail of the head-chuck. Fig. 9 is a sectional detail looking up on the line 9 9 of Fig. 1. Fig. 30 10 is a modified chuck for holding solid rods or bars, and Fig. 11 is a cross-section on line 35 11 11 of Fig. 10.

The object of my invention is to construct an automatic feed mechanism for pipe-polishing machines which will result in a material 40 reduction in the cost of polishing pipes, rods, and similar members; one which will turn out the greatest quantity of work within a given time; one which will polish a pipe within a minimum length of time; one which 45 shall be simple, cheap, and reliable, and one possessing further and other advantages better apparent from a detailed description of the invention, which is as follows:

Referring to the drawings, 1 represents an 50 overhead counter-shaft mounted in depending bearings 2 2 and provided with tight and loose pulleys 3 4, respectively, over which passes a belt 5, leading to a line-shaft or any source of driving power. (Not shown.) The belt 5 is controlled by a belt-shifter S of prevailing construction. The shaft 1 is pro-

vided with an intermediate pulley 6, from which leads downward a belt 7 to a pulley 8 on the shaft 9, which carries the polishing-disk 10, the shaft 9 being mounted in suitable 60 bearings 11 11 on the standard B. The counter-shaft 1 is likewise provided with a terminal elongated pulley 12, from which lead the open and cross belts 13 13', respectively, to the loose and tight pulleys 14 15, 65 carried by the screw or feed-shaft 16, the latter having intermediate bearings 17 at the top of the standard B and terminal bearings 18 at the top of the posts B'. The belts 13 13' are controlled by a belt-shifter S', being 70 adapted to be jointly brought over the loose pulleys 14 14, Fig. 1, or one belt over one loose pulley and one tight pulley on either side, as is obvious.

Adapted to travel over the threaded portion of the screw-shaft 16 is a nut 19, which forms the upper terminal of a swinging link or arm 20, and adapted to travel over the smooth portion of the screw-shaft is a ring 19', forming the upper terminal of a link or 75 arm 20', the end of the link 20 and the intermediate portion of the link 20' being connected by a channel bar or member 21, the groove or channel of the bar opening downward. Inserted into the channel of the bar 21, through 80 the open end adjacent the link 20, is the tongue 22 of an arm 23, which carries the tail-chuck 24, the latter being provided with a conical chuck-head 25, rotatable about the spindle of the chuck and held thereon by a 85 screw 26, operating in a peripheral groove 27 of the spindle, Fig. 7. The spindle may be retracted at any time sufficiently to release the pipe P, when it returns to engaging position under the action of the coiled spring 28, 95 surrounding the spindle and interposed between a disk or shoulder 29, carried thereby, and the end of the arm 23. Passing loosely through the looped end of the link 20' is the 90 rotatable spindle 24' of the head-chuck, the outer terminal of which is provided with a pulley 30, from which leads a belt 31 over the pulley 32, mounted on and feathered to and free to slide along the smooth portion of the screw-shaft 16, the said pulley terminating 105 in a flange 32', from which project a series of fingers 33, loosely engaging a peripheral groove 34 on the ring 19', Fig. 5. This specific engagement between the ring 19' and pulley 32 keeps these two members permanently 110 coupled together, traveling as they do in unison along the screw-shaft, as presently to

be seen. The inner end of the spindle 24' is supported in a bracket or arm 35, depending from the channel 21, the free end of said spindle terminating in a conical head 25', which 5 wedges itself into the adjacent end of the pipe P, Fig. 8, so that when rotation is imparted to the spindle 24' it will impart rotation to the pipe P, held between the head and tail chucks.

- 10 To prevent lateral vibration of the pipe as it is subjected to the abrading action of the polishing-disk 10, I provide an arm 36, pivoted at the base of the standard B, the free end of the arm being provided with a pair of 15 rollers 37, bearing against the pipe and held yieldingly thereto by a spring 38, which connects an intermediate point of the arm to the standard. Secured to the tongue 22 of the arm 23 is a tappet-arm 39, whose distance 20 from the end of the tail-chuck carried by the arm 23 is equal to the distance of the disk 10 from the adjacent end of the belt-shifter S', and secured to the ring 19' is a tappet-arm 39'. The tongue 22 when once adjusted 25 within the channel-bar 21 for any given length of pipe is clamped into position by the screw 40, and the object of having the arm 39 at a constant distance from the arm 23 and tail-chuck 24 is that it may be at a constant 30 distance from the adjacent end of the pipe irrespective of the length of the latter, so that the feed mechanism may reverse itself when the full length of the pipe has been advanced along the polishing-disk.

- 35 In Figs. 10, 11, I have shown a tail-chuck 41 and a head lathe-chuck 42 for carrying a solid rod R, intended to be polished, the modified forms of these two pieces making them specially applicable for holding solid rods. 40 Of course the chucks may be varied to suit special purposes.

The operation of the machine may be briefly described as follows: Motion being imparted to the counter-shaft 1 is transmitted to the 45 disk-shaft 9 and disk 10 through the medium of the belt 7. At the same time the operator shifts the belts 13 13', so as to bring one of the belts over its adjacent tight pulley 15, when the screw-shaft will be rotated in one 50 direction. The screw-shaft in turn imparts rotation to the sliding pulley 32, which in turn through the medium of the belt 31 rotates the spindle 24' of the head-chuck, the latter imparting rotation to the pipe P. As 55 the screw-shaft 16 rotates, however, it will cause the nut 19 to travel over it in one direction, the latter in turn causing the entire channel-bar 21 and the link 20', with its ring 19' and pulley 32, coupled thereto, to slide 60 along the shaft. The pipe P being in turn suspended from the channel-bar 21 (through the connecting-arm 23 and arm 20') will likewise travel lengthwise, so that as the pipe rotates about its axis to present different portions of its periphery to the polishing-disk it

will at the same time travel longitudinally to present its entire length to the disk, (which is stationary.) By the time the end of this longitudinal movement or stroke is reached the tappet-arm 39 will strike the adjacent end of the upper horizontal member of the belt-shifter S', shifting the belts 13 13' to the opposite pair of tight and loose pulleys, thus reversing the motion of the screw-shaft, when the parts will travel longitudinally in the opposite direction until the tappet-arm 39' strikes the adjacent end of the belt-shifter S', when the belts 13 13' will again be shifted, bringing the parts in position for another return stroke, and so on indefinitely until the 80 pipe is completely cleaned or polished, the machine being entirely automatic in this particular. Of course with one stroke of the pipe the latter will revolve with the disk and with the opposite stroke against the disk, being that with each reverse rotation imparted to the shaft 16 a reverse rotation is imparted to the sliding pulley 32, which is feathered to the shaft. The pulley 32 being connected to the ring 19' by the fingers 33 it follows that 85 the parts 19 19' 21 20 20' 23 35 30 31 32 travel as a unit or frame suspended from the shaft 16, the pipe P rotating at the free end of the frame. As the pipe travels longitudinally along the revolving periphery of the disk 10 90 the spring 38 allows the arm 36 to yield sufficiently and yet prevent any undue lateral vibrations in the pipe.

Having described my invention, what I claim is—

1. In combination with a rotating abrading or polishing disk, a screw-shaft, a frame traveling along the shaft, means on the frame for supporting the article to be polished, and a yielding member for pressing the article 105 against the disk during the rotation of the latter, substantially as set forth.

2. In combination with a rotating abrading or polishing disk, a screw-shaft, a frame for supporting the article to be polished, depending from the shaft and movable longitudinally along the same, means for imparting rotation to the screw-shaft, and intermediate connections between the shaft and article to be polished for rotating the latter during the 110 rotation of the disk, and during the longitudinal travel of the article along said disk, substantially as set forth.

3. In combination with a rotating disk, a rotatable screw-shaft, a frame depending therefrom, means for reciprocating the frame along the shaft during the rotation of the latter, suitable rotatable chucks carried by the frame for supporting and rotating the article to be polished, and intermediate connections 120 between the shaft and chucks for imparting rotating to the latter and to the article carried thereby during the reciprocations of the frame, substantially as set forth.

4. In combination with a rotating disk, a 130

rotatable screw-shaft, belt-operated pulleys for the shaft, a belt-shifter for the pulleys, a frame depending from the shaft and having a nut engaging the threaded portion thereof, chucks having rotatable members mounted in the frame for the support of a pipe or article to be polished, a sliding pulley feathered along the smooth portion of the shaft and rotating therewith, a pulley on the adjacent chuck member, belt connections between said pulley and the sliding pulley on the shaft, and tappet members or arms carried at opposite ends of the frame for reversing the rotation of the screw-shaft at the ends of the longitudinal strokes of the frame, substantially as set forth.

5. In combination with a rotating disk adapted to operate upon a rotating and longitudinally-movable article, a spring-controlled arm disposed in the plane of rotation of the disk and bearing against the article from the opposite side to prevent undue vibration thereof, substantially as set forth.

6. In combination with a rotating disk adapted to operate upon a rotating and longitudinally-movable cylindrical article, a yielding arm disposed in the plane of rotation of the disk and bearing against the article from the opposite side and prevent lateral vibration thereof, and a pair of rollers mounted on the arm and engaging the article, substantially as set forth.

7. In combination with a rotating disk, a rotatable screw-shaft, a frame depending therefrom and adapted to reciprocate along the shaft, a channel-bar forming a member

of said frame, an arm having a tongue for insertion into one end of the channel of said bar, a tappet-arm secured to said tongue, a tail-chuck carried by the arm aforesaid, a 40 head-chuck at the opposite end of said reciprocating frame, means for imparting rotation to the head-chuck from the screw-shaft, and in turn to the article held between the chucks, a second tappet-arm at the opposite end of 45 the frame, and reversing mechanism for the shaft controlled by said tappets, substantially as set forth.

8. In combination with a rotating screw-shaft having a smooth portion, a frame having portions traveling over the screw-threaded and smooth portions respectively, means for attaching an article to be operated on, to the frame, a belt-pulley slidably feathered to the shaft along the smooth portion thereof, a 50 peripheral groove formed in the adjacent portion of the frame traveling over the smooth section of the screw-shaft, fingers formed on the feathered pulley and loosely 55 engaging the groove aforesaid, and belt connections between the feathered pulley and the adjacent end of the article supported in the frame for imparting rotation to said article during the longitudinal travel of the frame along the screw-shaft, substantially as 60 set forth.

In testimony whereof I affix my signature in presence of two witnesses.

JAMES D. WALSH.
